UNITED STATES PATENT OFFICE.

HARRY W. MILLER, OF CHICAGO, ILLINOIS, ASSIGNOR TO ERO MANUFACTURING COMPANY, OF CHICAGO, ILLINOIS, A CORPORATION OF ILLINOIS.

SIDE-CAR CENTER BRACE.

1,403,019.

Specification of Letters Patent. Patented Jan. 10, 1922.

Application filed January 14, 1921. Serial No. 437,201.

To all whom it may concern:

Be it known that I, HARRY W. MILLER, a citizen of the United States of America, and a resident of Chicago, in the county of Cook, State of Illinois, have invented certain new and useful Improvements in Side-Car Center Braces, of which the following is a specification.

This invention relates to resilient center braces for the connection between motor cycles and their side cars, and has for its object:—

To provide a structural formation and association of the brace parts whereby a substantial bracing is attained with a desired flexibility and prevention of jar transmission from the car to the motor-cycle and vice versa, and which is adapted for attachment to car bodies of different widths in a ready and effective manner, all as will hereinafter more fully appear.

In the accompanying drawing:—

Fig. 1, is a perspective view illustrating the general arrangement of the present center brace, the motor-cycle and side car being shown in dotted lines.

Fig. 2, is a detail longitudinal sectional elevation of the outer portion of the center brace and showing its attachment to transverse shaft of the side car.

Fig. 3, is a detail transverse section on line 3—3 Fig. 2.

Like reference numerals indicate like parts in the different views.

Referring to the drawing, 1 designates the transverse shaft by which the running gear of the side car is connected to the frame of the motor-cycle by the usual hinged or pivotal connection 2.

3 designates the usual diagonal center brace having a curved shape and attached at one end to the frame of the motor-cycle by a hinge or pivot connection 4 of any usual and suitable construction. In the present improvement the other and outer end of the brace 3 is of a tubular form, extending parallel with the aforesaid transverse shaft 1 of the side car, and connected thereto in an adjustable manner by means as follows.

5 designates a split clip sleeve fitting the shaft 1 and adapted to be clamped thereon at any desired transverse location by a clamping bolt 6 passing through orificed ears at one end of the counterpart halves of the clip.

7 designates a stud bolt passing through orificed ears at the other end of the clip sleeve 5 to attach the same together, and in the present improvement said stud bolt carries at one end a spherical head 8 adapted for bearing engagement with a resilient connection of the center brace 3 as follows.

9 designates an abutment plug or block fixed in the bore of the center brace 3 near the outer end of the same, and 10 designates a companion plug or block screwed or otherwise fitted into the outer end of the center brace 3 in spaced relation to said fixed plug or block 9, with the intermediate tubular wall of the brace 3 aforesaid formed with an elongated slot 3' for the reception and movement of the shank portion of the stud bolt 7 aforesaid.

11 and 12 designate bearing plates or disks arranged in the bore of the center brace 3 and adapted for engagement with the opposite sides of the spherical head 8 of the stud bolt 7 aforesaid.

13 and 14 designate cushion springs arranged between the bearing disk 11 and the fixed block 9 and between the bearing disk 12 and the outer plug 10, respectively, and adapted to resiliently hold said bearing disks in contact with the spherical head 8 aforesaid.

15 designates a segmental cap or cover plate associated with the shank of the stud bolt 7 and with the elongated slot 3' of the center brace 3 and adapted to cover or close said slot against the entry of dust, etc., while permitting a normal independent movement of the shank of said stud bolt in said slot.

16 designates an adjustable bearing disk interposed between the outer plug 10 aforesaid and the adjacent end of its spring 14.

17 designates an adjusting screw arranged axially in the plug 10, to afford means for regulating the tension of both the springs 13, 14, in as much as that with the present construction an increase or a decrease in tension of one spring will automatically effect a corresponding change in the tension of the companion spring.

Having thus fully described my said invention what I claim as new and desire to secure by Letters Patent, is:—

1. A center brace for the side cars of motor-cycles comprising in combination, a tubular diagonal brace member having an elongated slot near its outer end, a clip mem-

- ber adapted for attachment to a transverse shaft of the running gear of the side car and carrying a stud bolt provided with a spherical end head with the stem of the stud bolt having movement in said elongated slot, bearing disks arranged in the bore of the brace and having bearing against the opposite sides of said spherical head, and cushion springs individual to said bearing disks.
- 10 2. A center brace for the side cars of motor-cycles comprising in combination, a tubular diagonal brace member having an elongated slot near its outer end, a clip member adapted for attachment to a transverse shaft of the running gear of the side car and carrying a stud bolt provided with a spherical end head with the stem of the stud bolt having movement in said elongated slot, bearing disks arranged in the bore of the brace and having bearing against the opposite sides of said spherical head, cushion springs individual to said bearing disks, and means for adjusting the tension of said springs.
- 25 3. A center brace for the side cars of motor-cycles comprising in combination, a tubular diagonal brace member having an elongated slot near its outer end, a clip member adapted for attachment to a transverse shaft of the running gear of the side car and carrying a stud bolt provided with a spherical end head with the stem of the stud bolt having movement in said elongated slot, a cover plate associated with said slot and stud bolt, bearing disks arranged in the bore of the brace and having bearing against opposite sides of said spherical head, and cushion springs individual to said bearing disks.
- 30 4. A center brace for the side cars of motor-cycles comprising in combination, a tubular diagonal brace member having an elongated slot near its outer end, a clip mem-
- ber adapted for attachment to a transverse shaft of the running gear of the side car and carrying a stud bolt provided with a spherical end head with the stem of the stud bolt having movement in said elongated slot, bearing disks arranged in the bore of the brace and having bearing against the opposite sides of said spherical heads, a fixed bearing plug arranged in the bore of the brace member near one end of said elongated slot, a bearing plug fixed in said brace member near the other end of said slot, individual springs arranged between the respective plugs and disks, an adjustable bearing disk arranged between the bearing plug and its springs and an adjusting screw arranged axially in said plug.
- 45 5. A center brace for the side cars of motor-cycles comprising in combination, a tubular diagonal brace member having an elongated slot near its outer end, a clip member adapted for attachment to a transverse shaft of the running gear of the side car and carrying a stud bolt provided with a spherical end head with the stem of the stud bolt having movement in said elongated slot, bearing disks arranged in the bore of the brace and having bearing against the opposite sides of said spherical head, a fixed bearing plug arranged in the bore of the brace member near one end of said elongated slot, a bearing plug fixed in said brace member near the other end of said slot, individual springs arranged between the respective plugs and disks, an adjustable bearing disk arranged between the bearing plug and its spring, an adjusting screw arranged 55 axially in said plug, and a cover plate associated with said elongated slot and said stud bolt.
